UNITED STATES PATENT OFFICE.

WALTER P. MURPHY, OF CHICAGO, ILLINOIS

SHEET-METAL CAR END.

1,265,239.

Specification of Letters Patent. Patented May 7, 1918.

Application filed August 7, 1912. Serial No. 713,806.

To all whom it may concern:

Be it known that I, WALTER P. MURPHY, a citizen of the United States, residing at Chicago, in the county of Cook and State 5 of Illinois, have invented certain new and useful Improvements in Sheet-Metal Car Ends, of which the following is a specification.

My invention relates to the construction 10 of railway cars, and the invention has for its primary object to provide a new and improved car end structure which can be very economically constructed, which may be readily repaired in case of damage, and, 15 which will be capable of withstanding the heavy strains and stresses exerted against the end structure of railway cars due to impacts from the outside, the shifting of the cargo when the car starts and stops, and 20 other causes well understood by railroad men.

The invention has for further objects to provide such other new and improved constructions, arrangements and devices relating 25 to railway car end structures as will be hereinafter described and claimed.

The invention is illustrated in the accompanying drawings, wherein—

Figure 1 is an end elevation of a railway 30 box car provided with the sheet metal end structure of my invention.

Fig. 2 is a sectional plan taken on line 2—2 of Fig. 1.

Fig. 3 is a vertical sectional elevation 35 taken on line 3—3 of Fig. 1, looking in the direction of the arrows.

Fig. 4 is a detail of one of the end sheets or bands, and

Fig. 5 is an enlarged detail in section 40 showing the means for securing the lower end sheet or band to the under frame of the car.

Fig. 6 is a fragmentary end elevation with 45 part of the upper end sheet broken away to show the relation of the ridge pole and the elements forming the end plate.

Like characters of reference designate like parts in the several figures of the drawings.

The sheet metal car end of my present 50 invention consists of a number of sheets or bands of metal extending from side to side of the car, attached to each other and to the side walls, roof structure and end frame of the car, and provided with hollow reinforcing ribs as will be hereinafter more particularly described.

Referring to the drawings which show a wooden box car of standard construction (obviously the car end of my invention might be used on railway cars of different 60 construction from the one shown), 10 designates the corner posts at one end of the car, 11 the end sill, 12 the end plate, 13 the ridge pole, 14 the outer sheathing, 15 the inner sheathing, 16 the roof, and 17 the 65 flooring of the car.

I have shown the sheet metal end structure as consisting of seven sheets or bands of metal 18 each about fifteen inches wide. Obviously any desired number could be used. 70

These bands are formed on their outer edges with the angular flanges 19 by means of which they are bolted to the corner posts 10. Each band is overlapped upon the one below it and the overlapping portions riveted together as indicated at 20. These overlaps 75 constitute, in effect, strengthening ribs extending horizontally across the car. The construction makes the end impervious to rain, snow, and the like. Each of the bands 80

18 is preferably formed with the hollow rib 21 which is widest and deepest at the center and tapers in width and depth toward the edges of the sheet. Above and below the centrally bulging ribs 21 are hollow ribs or 85

corrugations 22 which may or may not be tapered as desired. It will be seen that this structure is very stiff, strong, and is well 90 calculated to withstand the shocks, pressures and stresses which are exerted against the end of a railway car. The span from corner post to corner post is considerable so that

it is desirable that the sheets or bands constituting the end structure be stronger and stiffer at the middle than at the edges. This 95 is provided for by forming each band with the hollow rib 21 which is wide and deep at the middle. The smaller ribs prevent any local distortion due to the thrust of some particular piece of the cargo. The fact that 100 the bands or sheets are comparatively narrow, as I make them by preference, reduces the cost of manufacture and also the cost of repair in the event that one of the bands becomes injured and has to be replaced.

The lower band 18^a preferably overlaps 105 and covers the outer face of the end sill 11, the overlapping flange being bolted or otherwise secured to the sill. For example, the truss rods 23 may extend through the sill 110 and end sheet. In order to insure a tight and secure joint between the end sheet 18^a

and the end sill, which is particularly desirable when the car is likely to be used as a grain car, an angle bar 24 is interposed between the top of the end sill and the flooring 5 17, and the end sheet secured to the angle bar by rivets 25. The angle bar may be attached to the sill by bolts 26.

The upper band or end sheet 18^b preferably overlaps the end plate 12 and the end 10 of the ridge pole in the same manner. By employing an angle bar 27 secured to the end plate by bolts 26 to which the end sheet may be riveted, as indicated at 28, it will not be necessary to bolt through the end plate 15 horizontally and this results in a construction which is more surely waterproof. Besides this the angle plate at the top of the end structure reinforces and strengthens the structure, as does the angle plate at the sill, 20 and particularly gives rigidity to the edge of the plate which by standing in front of the ridge pole checks the tendency of the ridge pole and roof to shift longitudinally by its inertia when the car suddenly starts 25 or stops.

While I have described my invention in a certain preferred embodiment, it will be readily understood that some modifications might be made without departure from the 30 invention. Therefore I do not wish to be understood as limiting the invention to the particulars shown and described.

I claim:

1. In a railway car, the combination with 35 a wooden end sill and the flooring of the car, of a sheet metal end panel which overlaps the outer face of the sill and is secured thereto, and an angle-bar extending across the car from side to side and seated on said 40 sill with its horizontal flange secured thereto and extending under said flooring, and its vertical flange secured to said end panel

whereby an angular reinforcement and weather-protecting device is provided for said end sill.

2. In a railway car, the combination with a wooden end sill, of a sheet metal end panel which overlaps the outer face of the sill and is secured thereto, and an angle-bar extending across the car from side to side and seated on said sill with its horizontal flange secured thereto and its vertical flange secured to said end panel whereby an angular reinforcement and weather-protecting device is provided for said end sill.

3. In a railway car, the combination with a wooden end sill and the longitudinal truss rods of the car, of a sheet metal end panel which overlaps the outer face of the sill and is secured thereto, and an angle-bar extending across the car from side to side and seated on said sill with its horizontal flange secured thereto and its vertical flange secured to said end panel whereby an angular reinforcement and weather-protecting device is provided for said end sill; said truss rods extending through said end sill and overlapping portion of the panel and anchored against the latter.

4. In a railway car, the combination with 70 the roof and ridge-pole of the car, of a sheet metal end structure which extends above the bottom of the ridge pole to form an abutment for the ridge pole to prevent longitudinal shifting of the roof, and a supporting 75 and rigidifying member which extends across the upper portion of the end structure on which the ridge pole rests and to which the end structure is secured.

WALTER P. MURPHY.
